CLAIM

The ornamental design for a door hold, as shown and described.

DESCRIPTION

FIG. 1 is a perspective view of a first embodiment of a door hold, shown in closed position, in accordance with the present invention;

FIG. 2 is a front view thereof;

FIG. 3 is a top view thereof;

FIG. 4 is a right side view thereof;

FIG. 5 is a bottom view thereof;

FIG. 6 is a perspective view thereof shown in open position;

FIG. 7 is a perspective view of a second embodiment of a door hold of the invention; and,

FIG. 8 is a front elevational view thereof.
